UNITED STATES PATENT OFFICE

140,747

DESIGN FOR A GLASS CANDLE HOLDER OR ARTICLE OF SIMILAR NATURE

Charles L. Fordyce, New York, N. Y., assignor to
Pittman-Dreitzer & Co., Inc., New York, N. Y.,
a corporation of New York

Application December 26, 1944, Serial No. 117,089

Term of patent 14 years

(Cl. D48—2)

To all whom it may concern:

Be it known that I, Charles L. Fordyce, a citizen of the United States of America and a resident of New York, in the county of New York and State of New York, have invented a new, original, and ornamental Design for a Glass Candle Holder or Article of Similar Nature, of which the following is the specification, reference being had to accompanying drawing, forming a part thereof.

Figure 1 is a side elevational view of my glass

candle holder or article of similar nature showing my new device.

Figure 2 is a top plan view of the article shown in Figure 1.

I claim:

The ornamental design for a glass candle holder or article of similar nature, substantially as shown.

CHARLES L. FORDYCE.
